UNITED STATES PATENT OFFICE.

ROBERT WILLIAM DAVIS, OF EAST ORANGE, NEW JERSEY.

SWIMMING APPLIANCE.

1,239,088.

Specification of Letters Patent. Patented Sept. 4, 1917.

Application filed May 2, 1917. Serial No. 165,924.

To all whom it may concern:

Be it known that I, ROBERT WILLIAM DAVIS, a citizen of the United States, residing at 447 Norwood street, East Orange, in 5 the county of Essex and State of New Jersey, have invented a new and useful Swimming Appliance, of which the following is a specification.

My invention relates to improvements in 10 swimming appliances for propulsion and partial support; and the objects of my improvements are: first, to provide for a swimmer a means for exerting an uniform force against the water for propulsion and support; second, to provide for a swimmer an appliance for propelling or supporting himself without the waste of energy found in swimming with no appliance; third, to provide a swimming appliance whose parts are 20 detachable for portability; and fourth, to provide a simple swimming appliance consisting of a screw propeller, whose thrust is exerted on a stirrup for the swimmer's foot, and which is turned by his hands.

25 I attain these objects by the device illustrated in the accompanying drawings, in which—

Figure 1 is a front elevation of the entire appliance; and Fig. 2 is a plan view of same.

30 Similar numbers refer to similar parts throughout the several views.

The screw propeller 1 consists of a hollow cylinder, on the outside of which two or more blades are mounted. The blades are 35 guyed backward (in direction of axis) and forward (in direction of rotation) by the guy wires 2. The hollow cylindrical hub, with comparatively thin wall, rotates and moves ahead without moving much water, 40 and therefore without wasting much energy. The guy wires 2 strengthen the blades in the direction of resultant force, which is also the direction of least strength of the blades themselves.

45 The double crank 3 is a round metal rod with two right angle bends in it. Near one end it is countersunk on opposite sides for the cone point headless set screws 4, which screw in lugs on propeller 1, and hold crank 50 3 firmly therein. The other end of the crank 3 is riveted over the end of the outer handle 5. The inner handle 5 is secured between the propeller and one of the bends in the crank. The handles 5 are free to turn on the rod of 55 the crank 3.

The thrust of the propeller 1 is exerted on the foot of the swimmer by means of the three wires 6 connecting the hub of the propeller 1 with the three-prong header 7, which, with collar 8 and eye piece 9, forms 60 a turning joint, which is connected to stirrup 14 by means of straps 10 and 12, eye piece 13, and buckle 11, which adjusts the length of the whole thrust rigging.

Since my previous application, Serial No. 65 164672, covers the simpler form of this swimming appliance, I shall not repeat those claims, but I now claim:—

1. In a swimming appliance, a screw propeller having a comparatively large hollow 70 cylindrical hub on whose outside two or more blades are mounted, and to which a crank is fastened for turning same.

2. In a swimming appliance the combination of a screw propeller, a double crank 75 suitable to turn said propeller with both hands, and an axial-tension or thrust rigging provided with means for adjusting its length and suitable to apply the axial-tension of said propeller on swimmer's foot. 80

3. In a swimming appliance the combination of a screw propeller having an annular hub, a 180° double hand crank detachably secured thereto, and an axial-tension or thrust rigging provided with a turning 85 joint, a means for adjusting its length, and a stirrup suitable to apply the axial-tension of said propeller to swimmer's foot.

4. In a swimming appliance the combination of a screw propeller having a comparatively large annular cylindrical hub on which the blades are mounted and to which they are guyed forwardly in direction of rotation and backwardly in direction of axis, a 180° double hand crank (made 90 of round metal rod with two right-angle bends in opposite directions in it) detachably and firmly secured to said propeller and carrying two loose handles, and an axial-tension or thrust rigging connected to 100 said annular hub by means of three wires 120° apart and provided with a turning joint, a means for adjusting its length, and a stirrup suitable to apply the axial-tension of said propeller to the swimmer's foot. 105

5. In a swimming appliance, a screw propeller consisting of a hollow cylindrical hub, and blades on the outside of said hub, a boss also on the outside of the hub, and a turning crank fastened to said boss. 110

6. In a swimming appliance, a screw propeller consisting of a hollow cylindrical hub, and blades on the outside of said hub, a crank fastened to the hub for turning the propeller by hand, and a thrust rigging swiveled to the propeller and having means for attachment to a swimmer's foot.

7. In a swimming appliance, a screw propeller consisting of a hollow cylindrical hub and blades on the outside of the hub, and a turning crank fastened to the hub and having a portion arranged diametrically of the

hub, there being handles at both ends of said portion.

8. In a swimming appliance, a screw propeller consisting of a hollow cylindrical hub and blades on the outside of said hub, a turning crank fastened to the hub and having a portion arranged diametrically of the same, and loose handles at the opposite ends of said diametrically arranged portion.

All that is claimed is substantially as specified and for the purpose set forth.

ROBERT WILLIAM DAVIS.
